UNITED STATES PATENT OFFICE.

WINTHROP K. HOWE, OF ROCHESTER, NEW YORK, ASSIGNOR TO GENERAL RAILWAY SIGNAL COMPANY, OF ROCHESTER, NEW YORK.

CONTINUOUS INDUCTIVE TRAIN-CONTROL SYSTEM.

Application filed November 27, 1925. Serial No. 71,671.

This invention relates to automatic train control and more particularly concerns a train control system of the continuous inductive type.

In general, train control systems are designed to add a certain element of safety to train operation over and above that which is afforded by the usual operation of the train by the engineer in accordance with the indications of wayside signals. To accomplish this purpose, it has been considered advisable to design train control systems in such a manner that the engineer will be encouraged to maintain a constant vigilance in his observation of the wayside signals, and to operate the train in accordance with their indications. One system which carries out this idea of encouraging the observance of signal indications by the engineer employs so-called acknowledging means, that is, a suitable manually operable means is provided which must be properly operated by the engineer at points along the trackway where traffic conditions, as indicated by the wayside signals or by the cab signals, change from clear to caution or from caution to danger. In other words, in certain of the acknowledging systems heretofore proposed, the engineer is required to observe and acknowledge the first unfavorable signal indication encountered, further successive danger or stop signals having no further effect on the car-carried apparatus and requiring no further acknowledgment by the engineer.

The acknowledgment of successive danger or stop signals in an automatic train control system of the well known continuous inductive type is particularly desirable. In this type of system, favorable traffic conditions ahead are usually indicated by the flow of alternating current in the track rails or other wayside conductors, a change to unfavorable conditions being indicated by the fact that this current ceases to flow. As a train proceeds over trackway territory in which unfavorable traffic conditions exist, the trackway current remains off, and the engineer is not reminded by any further operation of the car-carried apparatus that he is proceeding in dangerous territory. It is evident that suitable means for requiring the performance of a manual acknowledging act at predetermined intervals when the train is passing successive stop or danger signals is very desirable, as it is most important to maintain the engineer's vigilance while he is operating in trackway

territory where continued dangerous conditions exist ahead.

With the above and other considerations in mind it is proposed in accordance with the present invention to provide an automatic train control system of the continuous inductive type in which means are provided for enforcing the acknowledgment of all unfavorable indications of the wayside signals, and more specifically it is proposed to provide a system of this type in which a restrictive penalty is imposed if the engineer does not perform a suitable manual act when the first and all subsequent successive unfavorable signals are encountered.

Other objects, advantages and characteristic features of the invention will become apparent as the description thereof progresses.

In describing the invention in detail, reference will be made to the accompanying drawing in which the trackway and car-carried apparatus of a simplified continuous inductive train control system of the two-position type, embodying the present invention, has been shown in a diagrammatic manner.

Referring to the drawing, the trackway apparatus is of the usual type used in connection with continuous inductive train control, and as this equipment is well known to those skilled in the art, it will be rather briefly described.

The track rails 1 are divided into blocks by the insulating joints 2, the block I and the ends of the two adjacent blocks H and J having been shown. In order to simplify the disclosure, the corresponding elements and devices in the various blocks have been indicated by like reference characters having distinctive exponents. The normal direction of traffic over the trackway is indicated by the arrow.

The usual track relays 3 are connected across the track rails at the entrance end of each block, being normally energized by the track battery 4 connected across the track rails at the exit end of each block as shown. Alternating train control current is supplied to the two track rails in series through the transformer 5, the secondary winding of which is connected across the track rails in series with the battery 4 as clearly shown. The transformer 5 is energized from a second transformer 6 through a circuit including the contact finger 7¹ and front contact of the track relay 3¹ of the first block in advance, the transformer 6 being energized from a

transmission line or other suitable source of alternating current.

Wayside signals of the semaphore, color light, or other suitable type are preferably used in connection with the present invention, and the semaphore signals Z have been conventionally illustrated in the drawings at the entrance end of each block, the well known operating devices and circuits for these signals being omitted to simplify the disclosure.

In carrying out the present invention, it is necessary to transmit an impulse to the vehicle for a short distance of travel in each block under unfavorable traffic conditions, and this is conveniently accomplished by providing so-called track loops near the exit end of each block. Each track loop 8 consists of a wire arranged to extend parallel to the track rails for a short distance near the exit end of each block, alternating train control current being supplied to this wire from the transformer 6 through a circuit including the contact finger 7¹ and back contact 9¹ of the track relay 3¹ of the first block in advance. The track loop 8 is so mounted as to produce an alternating magnetic field near the track rail 1 which induces voltages in the receiving apparatus on the vehicle in the same manner as would the field from an alternating current in the track rails. The track loops in the various blocks are of equal length for reasons hereinafter described.

From the description of the trackway apparatus given above, it will be evident that the presence of a train in a given block, say the block J, shunts the track circuit and train control current from the track rails of that block in the rear of the train, and de-energizes the track relay 3¹ at the entrance end of the block. The de-energization of the track relay 3¹ cuts off the train control current from the track rails of the block I, and energizes the track loop 8 of that block. Thus no train control current flows in the track rails of an occupied or danger block behind the train located therein, or in the track rails of a caution block, that is, the first block to the rear of an occupied block, and the trackloop in the caution block is energized with train control current.

A railway vehicle has been conventionally represented in the block H by the wheels and axles 10. This vehicle is provided with the usual receiving coils 11 which are mounted ahead of the leading axle of the vehicle and in inductive relation to the track rails 1. The coils 11, which may or may not be provided with laminated iron cores, are so connected that voltages induced therein as a result of alternating currents flowing in opposite directions in the two track rails are additive. The receiving coils 11 are connected in series with the input circuit of a suitable amplifying device A which may take any one of a number of preferred forms, such as an

audion tube amplifier of the well known type. This receiving input circuit may be tuned to resonance at the frequency of the train control current by means of a condenser of suitable capacity if desired. The output circuit of the amplifier A is connected to a suitable quick acting main car relay MR, which may be of the alternating current or of the direct current type.

As certain of the vehicle controls are dependent upon the vehicle speed, a suitable speed responsive device is provided. This speed responsive device may take any suitable form, and has been shown as a simple centrifuge G, of the fly ball type comprising the usual fixed collar 12 and slidable collar 13 mounted on a shaft 14 and normally biased apart by a spring 15. The links 16 and 17 carrying the weights 18 are pivotally connected to the collars 12 and 13, the movable collar 13 having a groove therein which is operatively engaged by a lever 19 connected to a speed shaft 20. The arrangement is such that the upward movement of the slidable collar 13 as the speed of the shaft 14 increases, turns the speed shaft 20 through the lever 19 in a clockwise direction. The shaft 14 is suitably connected through gearing, belting or other suitable means, to an axle of the vehicle.

The speed shaft 20 carries a cam 21 which is engaged by a suitable movably mounted contact finger 22, biased to the position shown, the arrangement being such that the finger 22 is moved by the cam 21 to engage a stationary contact 23 when the speed shaft 20 is in a position corresponding to a very low vehicle speed, such as one or two miles per hour. If desired, the cam 21 may be arranged to close the contacts 22 and 23 only when the vehicle is at a stop. The driving shaft 14 carries a worm gear 24 rigidly secured thereto, and this worm gear is engaged by a pinion 25, suitably secured to a shaft 26. The shaft 26 carries a second pinion 27 which is in continuous driving engagement with two gears 28 and 29.

The gear 28 is rotatably mounted on a shaft 30 which also carries a bracket 31 having three arms 32, 33 and 34, extending radially from the shaft 30. The arm 33 carries a gear 35 which is in driving engagement with gear 28. The arm 32 carries two gears 36 and 37 which are in driving engagement with each other and are driven by the gear 28, the gears 36 and 37 being located in a different plane from that of the gear 35. A cam shaft 38 is mounted adjacent to the gear 28, and carries two mutilated gears 39 and 40, fixed to the end thereof, the gear 39 being in the plane of the gear 35, and the gear 40 being in the plane of the gears 37 and 36. The arm 34 of the bracket 31 extends horizontally from the shaft 30 and is biased upwardly by a spring 41, this arm 34 together with the arms 33 and

32 being normally held in the position shown by the cam starter magnet 42. When the magnet 42 is de-energized, the gear 35 engages the gear 39 and turns the shaft 38 in one direction until the mutilated portion of the gear 39 is opposite the gear 35. The re-energization of the magnet 42 causes the gear 35 to disengage the gear 39 and the gear 37 to engage the gear 40, thus turning the shaft 38 in the opposite direction until it has reached its original position as shown with the gear 37 opposite the mutilated portion of the gear 40. It should be observed that the return or reverse speed of the shaft 38 when driven through the gears 36 and 37 is higher than the run-down speed when this shaft is driven through the gears 35 and 39 for the reason that the gears 37 and 40 are more nearly equal in diameter than are the gears 20 35 and 39.

The shaft 38 carries three cams, 43, 44 and 45, which are arranged to control the engagement of the movable contact fingers 46, 47 and 48 with their stationary contacts 49, 50 and 51, respectively, as hereinafter described.

The gear 29 drives a second cam shaft 52 through a reduction gear train comprising the pinion 53 fixed on the shaft 54 with the gear 29 and the gear 55 with the pinion 56 both fixed to the shaft 57. The shaft 57 is carried by a bracket 58 which is pivotally secured to the shaft 54 and is extended beyond the shaft 57 to form a horizontally extended arm as shown. This horizontally extended arm of the bracket 58 is biased upwardly by the spring 59 and is normally held in the position shown by the cam starter magnet 60. A mutilated gear 61 is secured to the shaft 52 in a plane with the pinion 56, and the de-energization of the magnet 60 permits the spring 59 to move the arm 58 together with the pinion 56 into engagement with the gear 61. The shaft 52 is thereby rotated at a low speed as compared with the speed of rotation of the shaft 38, the extent of this rotation being limited by the mutilated portion of the gear 61. When the magnet 60 is again energized, the shaft 52 is returned to its normal position as shown by means of a spring 62.

The vehicle speed may be controlled in any suitable manner, and in the system shown, means are provided for controlling the vehicle speed in accordance with distance of travel from the point at which influences corresponding to unfavorable traffic conditions ahead are first received. This speed distance feature is provided for by means of a permissive speed cam 63 secured to the shaft 52 and engaging one end of a floating lever 64, the other end of which is moved by an arm 65 fixedly secured to the speed shaft 20. The movement of an intermediate point on the lever 64 is proportional to a function of the

vehicle speed and its distance of travel from the point at which the magnet 60 is de-energized and the shaft 52 initiated. The floating lever 64 operates a contact sector 66 through a link 67, the sector 66 being biased 70 in a counter-clockwise direction by the spring 68. The sector 66 operates a movable contact finger 69 through the roller 70, the finger 69 being normally biased to disengage its stationary contact 71, and being held in engagement therewith by the sector 66. As the vehicle speed increases, the sector 66 is turned in a clockwise direction, the contacts 69 and 71 being permitted to open when a given speed is reached, this speed being dependent upon the distance of vehicle travel from the point at which unfavorable traffic conditions are first encountered.

The vehicle-carried apparatus includes a manually operable acknowledging contactor, designated as a whole as N. This contactor may take any suitable form which is convenient for manual operation, and as shown comprises a vertically disposed shaft 72, slidably mounted in suitable supports and biased by 85 the spring 73 to normally remain in its raised position as shown. The shaft 72 carries an insulated movable contact member 74, which engages the stationary contacts 75 and 76 when the contactor is in its normal position 90 as shown, and connects the stationary contacts 77 and 78 when the contactor is depressed. An armature 79 is secured to the lower end of the shaft 72, and a magnet 80 is arranged directly below this armature in such a position that the energization of the magnet 80 will retain the contactor N in its operative position against the bias of the spring 73 with the contacts 77 and 78 bridged by the contact 74. The contactor N is preferably 100 mounted at some point in the locomotive cab at which it may be easily reached by the engineer.

In order that the engineer may be informed as to the point in the vehicle travel at which the acknowledging contactor N must be operated, a suitable cab signal S is provided. This signal may be of the audible or visible type and as shown comprises a simple incandescent light of the well known type. A protection relay PR is provided in conjunction with the acknowledging contactor N, this relay being of the well known direct current type and being provided with suitable quick acting contacts.

The vehicle brakes may be controlled in any suitable manner and by means of any one of a number of well known devices adapted for this purpose. As the initiation of an automatic brake application is usually accomplished by means of the deenergization of some suitable electro-magnetic device, the device K has been shown, it being assumed that the deenergization of a circuit through its windings will act in some suitable man-

ner to initiate an automatic application of the vehicle brakes. A stick relay R of the usual type is provided for use in connection with the device K as hereinafter described.

5 *Operation.*—As shown in the drawings, all of the track-way and car-carried devices and circuits are in their normal operating positions, that is, in the positions assumed with a train travelling at speed in a clear block and with all circuits and devices properly energized. In order to simplify the circuits, the letters B and C have been used to designate the opposite terminals of a suitable source of energy such as a storage battery.

15 Considering first the operation of the system shown under clear traffic conditions ahead, assume that the train under consideration is proceeding in the block H with no other train in either of the blocks I and J.

20 Under these conditions, train control current flows in the track rails of the block H ahead of the vehicle under consideration, and serves to induce voltages in the receiving coils 11. These voltages are impressed on the input

25 circuit of the amplifier A and cause the energization of the main relay MR. With the main relay MR energized, the cam starter magnet 42 is energized through a circuit which may be traced as follows:—from the 30 battery terminal B, contact finger 90 and front contact 91 of the relay MR, wire 92, and the winding of the magnet 42 to the battery terminal C. With the cam starter magnet 42 energized, the cam shaft 38 is retained

35 in the position shown, the contacts 46 and 49 being closed by the cam 43, and the contacts 48 and 51 being closed by the cam 45. With the contacts 46 and 49 closed, the cam starter magnet 60 is energized through the following 40 circuit:—from the battery terminal B, contacts 46 and 49, wire 96, back contact and contact finger 97 of the relay PR, wire 98, and the winding of the magnet 60 to the battery terminal C. The energization of the

45 main relay MR also causes the energization of the stick relay R, through a circuit which may be traced as follows:—from the battery terminal B, contact finger 81 and front contact of the main relay MR, wires 82 and 83, 50 front contact and contact finger 84 of the stick relay R, wires 85 and 86 and the winding of the relay R to the battery terminal C. The stick relay R is also energized through a

55 circuit including the contacts 48 and 51 of the cam 45, and the wire 94, which circuit is hereinafter traced. With the stick relay R energized, the brake applying device K is energized through a circuit which may be traced as follows:—from the battery terminal B, contact finger 69 and stationary contact 71, wire 87, contact finger 88 and front contact of the stick relay R, wire 89 and the winding of the device K to the battery terminal C. With the device K energized the

56 engineer in the usual manner and the train under consideration may proceed in the clear block without automatic restriction.

57 It is often desirable to so arrange the automatic control apparatus that the engineer 70 may not exceed a predetermined high speed limit. In order to accomplish this restrictive control, the sector 66 is so proportioned that with the speed distance cam 63 in the 75 normal position shown, the lever 65, connected to the speed shaft 20 acts to move the sector 66 into position to open the contacts 69 and 71 when the speed of the vehicle becomes excessive. When the contacts 69 and 71 are disengaged the energizing circuit for the device K, traced above, is broken at this 80 point, and an automatic application of the brakes results. This automatic brake application persists until the train speed is reduced below the high speed limit, at which time the contacts 69 and 71 are again closed by the sector 66, thus re-energizing the device K, and permitting the release of the brakes by the engineer.

85 Considering now the operation of the train under consideration under caution traffic conditions, assume that the train under consideration enters the block I when another train is located in the block J. Under these 90 conditions, no train control current flows in the track rails of the block I and hence the main relay MR is de-energized as soon as the train enters this block. The de-energization of the main relay MR causes the immediate de-energization of the cam starter magnet 42, 100

the energizing circuit for this magnet being broken by the disengagement of the contact finger 90 of the relay MR and its front contact 91. It should be observed that the stick 105 relay R is not de-energized by the retraction of the contact finger 81 of the main relay MR, as an alternate energizing circuit for this relay R exists, which circuit may be traced as follows:—from the battery terminal B, movable contact finger 48 and stationary contact 110

51 of the cam 45, wires 93, 94, 83 and 95, front contact and contact finger 84 of the relay R, wires 85 and 86 and the winding of the relay R to the battery terminal C. The de-energization of the cam starter magnet 42 115 permits the spring 41 to move the arm 34 upwardly, thus engaging the gears 35 and 39. The shaft 38 is then turned in accordance with the motion of the vehicle, and after a pre-determined distance of vehicle travel, 120

say 100 ft. the cam 43 permits the movable contact finger 46 to disengage its stationary contact 49. This opening of the contacts 46 and 49 breaks the energizing circuit for the cam starter magnet 60, which circuit has been 125

traced above, and the spring 59 moves the pinion 56 into engagement with the milled gear 61, thus turning the shaft 52 in accordance with the progress of the vehicle. After the vehicle has proceeded a slightly 130

65 vehicle brakes may be released by the engi-

greater distance into the caution block, say another 100 ft. one of the raised portions on the cam 44 moves the contact finger 47 into engagement with the stationary contact 50 thereof, thus completing an energizing circuit for the acknowledging signal which circuit may be traced as follows:—from the battery terminal B, movable contact 47 and stationary contact 50, wires 99 and 100, stationary contact 75, movable contact 74 and stationary contact 76 of the acknowledging contactor N, wire 101 and the signal S to the battery terminal C.

If the engineer is on the alert and has properly observed and recognized the caution indication of the wayside signal Z located at the entrance end of the block I, he is aware of the fact that he is operating under unfavorable traffic conditions ahead, and is therefore on the lookout for the operation of the acknowledging signal. The operation of the acknowledging signal S at this point informs the engineer that he has reached the point in the caution block at which he must operate the acknowledging contactor N, and, assuming in this case that the engineer does so operate the acknowledging contactor, a circuit is established for energizing the relay PR, which circuit may be traced as follows:—from the battery terminal B, stationary contact 77, movable contact 74 and stationary contact 78 of the contactor N, wire 102 and the winding of the relay PR to the battery terminal C. The energization of the relay PR causes its contact finger 103 to engage its front contact and the finger 97 to disengage its back contact. Just after the contacts 47 and 50 are closed by the cam 44, the cam 45 is turned to a position to permit the contact finger 48 to

disengage its stationary contact 51, thus breaking the energizing circuit for the stick relay R, which circuit has been traced above. If, however, the engineer has operated the acknowledging contactor N and energized the relay PR as described above, an alternate energizing circuit for the stick relay R is established before the energizing circuit through the contacts 48 and 51 is broken. This alternate energizing circuit may be traced as follows:—from the battery terminal B, front contact and contact finger 103 of the relay PR, wires 104, 94, 83 and 95, front contact and contact finger 84 of the relay R, wires 85 and 86 and the winding of the relay R to the battery terminal C. It should be noted that the engineer need not maintain the acknowledging contactor N in the depressed position for the distance of travel during which the contacts 48 and 51 of the cam 45 remain open, the acknowledging contactor being maintained in its closed position by means of the magnet 80 which is energized as soon as the acknowledging signal S is energized, the circuit being traceable as follows:—from the battery terminal B, movable

contact 47 and stationary contact 50 of the cam 44, wires 99 and 105 and the magnet 80 to the battery terminal C. As the train under consideration proceeds beyond the acknowledging point, the cam 45 again closes the contacts 48 and 51, thus completing energized circuit for the stick relay R which has been traced above, and the cam 44 opens the energizing circuit for the magnet 80, thus releasing the acknowledging contactor N. The relay PR is de-energized when the contactor N is released, the energizing circuit for the relay PR being completed as described above. At this point in the vehicle travel the cam shaft 38 has been turned through an angle of rotation of 180 degrees, and the gear 35 is opposite the mutilated portion of the gear 39. At this point the shaft 38 is no longer turned and the circuits established are maintained as the vehicle proceeds through the caution block.

The speed of the vehicle as it proceeds through the caution block is limited by the permissive speed mechanism described above. The cam shaft 52 is slowly turned through the reduction gears, moving the permissive speed cam 63 to impose more restrictive speed limits, and if the train speed is not maintained below these limits the sector 66 is turned to such a position that the contacts 69 and 71 are opened, deenergizing the brake applying device K and causing an automatic brake application which persists until the vehicle speed has been reduced to a value below the permissive limit. The train may thus proceed through the caution block under the restriction of the automatic control provided the engineer has properly acknowledged the caution signal just after entering this block.

As the train under consideration approaches the exit end of the caution block, the receiving coils 11 encounter the magnetic field surrounding the energized track loop 8, and the main relay MR is again energized. This energization of the main relay MR closes the energizing circuit for the cam starter magnet 42 through the contact finger 90 and front contact 91 of the main relay, this circuit having been traced above. The energization of the magnet 42 moves the gear 35 out of engagement with the gear 39 and causes the gear 37 to engage the gear 40, thus turning the cam shaft 38 in the reverse direction at a rapid rate. The length of track loop 8, is so arranged that the cam shaft 38 is returned about half way or 90 degrees while the vehicle traverses this track loop and this loop is the same length in each block, in order to obtain uniform operation at each loop. That is to say, the cam shaft 38 is returned to a point at which the cams 43, 44 and 45 maintain the contacts 46 and 49 open, the contacts 47 and 50 open, and the contacts 48 and 51 closed. As the train under consid-

eration leaves the track loop 8 and enters the occupied block J, the main relay MR is again de-energized and the cam starter magnet 42 is therefore de-energized, permitting the gear 35 to engage the gear 39 and again drive the shaft 38 in the run down direction. After a very short distance of vehicle travel, the contact finger 47 is again moved into engagement with its stationary contact 50 by the cam 44, thus energizing the acknowledging signal S and the magnet 80. At this point the engineer, having properly observed and recognized the danger indication of the signal Z¹ at the entrance to the block J, again operates the acknowledging contactor N, energizes the relay PR and establishes an alternate energizing circuit for the stick relay R while the contacts 48 and 51 of the cam 45 are opened. It should be noted that the cam shaft 52 was turned as the vehicle proceeded through the caution block to impose more and more restrictive speed limits as this caution block was traversed, the driving mechanism for this cam shaft being arranged so that the mutilated portion of the gear 61 comes opposite to the pinion 56 when the train is nearing the exit end of the caution block. As the cam shaft 38 is not returned far enough, when the track loop is encountered, to close the contacts 46 and 49 of the cam 43, the cam starter magnet 60 remains de-energized and the cam shaft 52 remains in its run down position, and continues to limit the train speed to the low permissive value as the train proceeds in the occupied block J.

The train under consideration now proceeds through the block J at the low permissive speed, and if the train in advance proceeds into the next advance block, thus imposing caution traffic conditions in the block J, the train under consideration encounters the energized track loop at the exit end of the block J and the engineer is forced to operate the acknowledging contactor N in the manner described above in connection with the block I. Thus as the train proceeds over trackway territory in which unfavorable traffic conditions ahead exist the engineer is required to perform a manual act by operating the acknowledging contactor N in each block in which dangerous traffic conditions exist.

If the engineer is not attentive to the indications of the wayside signals and to the operation of the acknowledging cab signal S, and runs into a block in which caution traffic conditions exist without operating the contactor N, the stick relay R is de-energized when the cam 45 reaches the point at which the contacts 48 and 51 are opened. The de-energization of the stick relay R causes the de-energization of the brake applying device K by opening the energizing circuit for this device through the contact finger 81 and front contact of the relay R. The de-energi-

zation of the device K causes an automatic brake application which persists until the train speed has been reduced to a very low value, say one or two miles per hour, at which speed the cam 21 moves the contact finger 22 into engagement with the stationary contact 23, and a pick up circuit for the stick relay R is established. This pick up circuit may be traced as follows:—from the battery terminal B, contacts 48 and 51 of the cam 45, wire 93, 94, 83 and 107, contact finger 22 and stationary contact 23 of the cam 21, wires 108 and 86, and the winding of the relay R to the battery terminal C. Once energized, the stick relay R moves its contact finger 84 into engagement with its front contact and a stick circuit is established through 48 and 51 for energizing this relay, which stick circuit has been traced above. The re-energization of stick relay R closes the energized circuit for the device K through the contact finger 88 and front contact of this relay; this energizing circuit has been traced above. With the device K energized the train under consideration may again proceed through the caution block under the control of the permissive speed mechanism.

If in a like manner the engineer fails to properly acknowledge the unfavorable indication of successive caution or danger signals at the points indicated by the operation of the acknowledging cab signal S, the train speed is automatically reduced to a very low value, practically to a stop, thus penalizing the engineer with the annoyance and delay occasioned by such automatic stop.

Means are provided for preventing the engineer from using the acknowledging contactor N to prevent an automatic brake application or speed restriction while travelling under unfavorable traffic conditions. Should the engineer secure or otherwise maintain the acknowledging contactor N in its depressed position in an attempt to avoid an automatic restriction, the energization of the protection relay PR, caused by the depression of the acknowledging contactor N, will break the energizing circuit to the cam starter magnet 60 at the contact finger 97, this energizing circuit having been traced above. The de-energization of the magnet 60 causes the cam shaft 52 to be turned as the vehicle progresses, and a restrictive speed limit is imposed as described above. This restrictive speed limit persists until the engineer releases acknowledging contactor N and permits the re-energization of the cam starter magnet 60.

It may be observed that when the cam shaft 38 is returned in the reverse direction in passing an energized track loop 8 under unfavorable traffic conditions, the contacts 48 and 51 are momentarily opened by the cam 45 and the contacts 47 and 50 are momentarily closed by the cam 44. This operation of the

contacts 47 and 48 need not be acknowledged by the engineer, as at this point the main relay MR is energized due to the fact that the track loop 8 is energized, and the stick relay R is energized through the front contact and contact finger 81 of the main relay and a circuit which has been traced above.

In train control systems of the continuous inductive type it is often found difficult to maintain the train control current continuously flowing in the track rails. Certain points such as switch frogs, cross overs, and the like are encountered at which these train control currents must be cut off for a short distance of vehicle travel. The present system is so designed that the momentary lack of train control currents in the track rails at these "dead sections," as they are sometimes called, will not impose a speed restriction or penalty. As a train equipped with the system shown encounters one of these dead sections along the trackway, the main relay MR is de-energized and the cam starter magnet 42 is also de-energized as described above, the stick relay R being maintained energized through the contacts 48 and 51 of the cam 45. The cam starter magnet 60 is not de-energized until the vehicle has proceeded a predetermined distance, say 100 ft. at which point the cam 43 permits the disengagement of the contact fingers 46 and 49. This distance preceding the de-energization of the magnet 60 is so arranged as to be in excess of the longest dead section distance ordinarily encountered in practice. After the dead section is traversed and the train control currents again effect the energization of the main relay MR, the cam starter magnet 42 is re-energized and the cam shaft 38 is returned to its original normal position by the gears 37 and 40, no automatic restriction having been imposed as a result of the momentary lack of control current in the track rails.

From the description given it will be observed that an extremely simple and efficient system of train control has been devised in which acknowledgment of all unfavorable signal indications by the engineer is enforced, and in which the failure of the engineer to properly acknowledge initial or successive unfavorable signal indications results in the imposition of a penalty. It is evident that by the use of this type of control system the engineer is encouraged to maintain a careful observation of the wayside signal indications, and is particularly encouraged to be vigilant in his observation of these indications while proceeding under unfavorable traffic conditions ahead.

Although the present invention has been described in connection with a rather specific system of train control embodying certain specific devices and circuits, it should be clearly understood that the invention is not limited

ed to the particular construction and arrangement shown, and that certain changes, modifications, and combinations might be made without departing from the scope of the invention as defined by the appended claims. 70

What it is desired to secure by Letters Patent is:—

1. In an automatic train control system of the continuous inductive two-position type, means for continuously transmitting influences from the trackway to a moving vehicle under favorable traffic conditions and for cutting off said influences under unfavorable traffic conditions ahead, car-carried apparatus comprising a control device responsive to said influences, speed restricting means controlled by said control device acting to automatically reduce the vehicle speed when said influences are not transmitted, apparatus associated with said control device for causing an automatic brake application and bringing the vehicle substantially to a stop when the train travels in adverse traffic territory without interfering with the proper functioning of said speed restricting means, and manually operable means acting if operated at predetermined successive points along the trackway under unfavorable traffic conditions to prevent the operation of said apparatus. 95

2. In an automatic train control system, trackway means for continuously transmitting influences to a moving vehicle under favorable traffic conditions and for cutting off said influences under unfavorable traffic conditions ahead, car-carried apparatus comprising a control device responsive to said influences, automatic speed restricting apparatus controlled by said control device and acting to impose increasingly restrictive speed limits as the vehicle proceeds under unfavorable traffic conditions and effecting a brake application if such speed limits are exceeded, and further automatic brake control apparatus for initiating an automatic brake application to bring the vehicle substantially to a stop if a manually operable device is not operated within predetermined distance intervals while the train is proceeding under unfavorable traffic conditions, said last mentioned means not interfering with the control of said speed restricting apparatus. 110

3. In an automatic train control system, trackway means for continuously transmitting influences to a moving vehicle under favorable traffic conditions and for cutting off said influences under unfavorable traffic conditions ahead, car-carried apparatus comprising a control means responsive to said influences, a distance operated device controlled by said control means and initiated when said influences are cut off, said distance operated device acting to initiate a speed control means and to set up a restrictive control after a predetermined distance of vehicle 130

- travel from the point at which said distance operated device is initiated, means controlled by said distance operated device for imposing an automatic brake application and bringing the vehicle to a stop at a predetermined distance from the point at which said speed control means is initiated, and manually operable means acting if operated to prevent said automatic brake application.
4. In an automatic train control system of the continuous inductive type in which a control current flows in the track rails under favorable traffic conditions and is cut off under unfavorable traffic conditions ahead, car-carried means responsive to said control current for controlling the vehicle speed in accordance with the flow of said current, means for automatically applying the vehicle brakes and bringing the vehicle substantially to a stop upon the entrance of the vehicle into a trackway section where said control current is cut off, manually operable means acting to prevent said automatic brake application if operated at a predetermined distance from the point at which said control current is cut off, and further trackway means at spaced points for initiating said automatic brake applying means when the vehicle is traveling under unfavorable traffic conditions unless said manually operable means is operated at a predetermined distance from said spaced points.
5. In an automatic train control system of the type in which influences are continuously transmitted from the trackway to a moving vehicle under favorable traffic conditions only, car-carried apparatus comprising a device driven in accordance with the motion of the vehicle and initiated when said influences are cut off, means for setting up a respective speed limit initiated by said device at a predetermined distance of vehicle travel from the point at which said influences are cut off, means controlled by said device for initiating an automatic brake application at a predetermined distance of vehicle travel from the point at which said restrictive speed means is initiated, said brake application bringing the vehicle substantially to a stop, spaced trackway means for operating said device to initiate an automatic brake application at predetermined successive points under unfavorable traffic conditions, and manually operable means acting to prevent said automatic brake applications if operated at said point where said influences are first cut off and at said predetermined successive points.
6. In an automatic train control system of the type in which control currents flow in the track rails under favorable traffic conditions and are cut off under unfavorable traffic conditions ahead, car-carried apparatus comprising a relay energized in response to the flow of said control currents, a control device adapted to be driven in accordance with the motion of the vehicle and initiated by the de-energization of said relay, said control device acting successively to initiate a restrictive control and to impose an automatic brake application after the vehicle has traveled a predetermined distance from the point at which said control currents are cut off and said relay is de-energized, current-carrying means at spaced points along the trackway for energizing said relay to reset said control device and thereby to impose said automatic brake application at said spaced points under unfavorable traffic conditions, manually operable means for preventing said automatic brake application, and means for releasing said automatic brake applications, if not prevented by said manually operable means, only after the vehicle has been brought substantially to a stop.
7. In an automatic train control system of the type in which control currents flow in the track rails under favorable traffic conditions and are cut off under unfavorable traffic conditions ahead, car-carried apparatus comprising a relay energized in response to the flow of said control currents, a control device adapted to be driven in accordance with the motion of the vehicle from an initial position to a run-down position when said relay is de-energized and to be reset to said initial position when said relay is re-energized, means controlled by said device for initiating an automatic brake application after said device has run down a predetermined amount, means for releasing said automatic brake application only after the vehicle has been brought to a stop, manually operable means for preventing said automatic brake application if operated before said device has run down said predetermined amount and further trackway means at spaced points for carrying control currents and momentarily energizing said relay at said points under unfavorable traffic conditions, whereby said device is reset at said points and an automatic brake application is initiated unless said manually operable device is operated at a predetermined distance from each of said points.
8. In an automatic train control system of the type in which control currents flow in the track rails under favorable traffic conditions and are cut off under unfavorable traffic conditions ahead, car-carried apparatus comprising a relay energized in response to the flow of said control currents, a control device adapted to be driven in accordance with the motion of the vehicle from an initial position to a run-down position when said relay is de-energized and to be reset to said initial position when said relay is re-energized, means for restricting the vehicle speed, initiated by said control device after said device has run down a predetermined amount, further means controlled by said device for initiating an automatic brake application after said device

- has run down a further predetermined amount, means for releasing said automatic brake application only after the vehicle has been brought to a stop, manually operable means for preventing said automatic brake application if operated before said device has run down said predetermined amount and further trackway means at spaced points for carrying control currents and momentarily energizing said relay at said points under unfavorable traffic conditions, whereby said device is reset at said points and an automatic brake application is initiated unless said manually operable device is operated at a predetermined distance from said points.
9. In an automatic train control system of the type in which control currents flow in the track rails under favorable traffic conditions and are cut off under unfavorable traffic conditions ahead, car-carried apparatus comprising a main relay energized in response to the flow of said control currents, a control device adapted to be driven in accordance with the motion of the vehicle from an initial position to a run-down position when said main relay is de-energized and to be reset to said initial position when said main relay is re-energized, a normally energized brake applying device acting to apply the vehicle brakes when de-energized, an energizing circuit for said brake applying device including a front contact of a stick relay and contacts of a permissive speed device, said permissive speed device acting to open said contacts if the vehicle speed exceeds a predetermined value after said device is initiated, a stick circuit for said stick relay closed by said control device when in its initial position and opened after said control device has run down a predetermined amount, an alternative stick circuit for said stick relay, manually operable means for closing said alternative stick circuit, means operated by said control device for initiating said permissive speed device after said control device has run down a predetermined amount, a pick-up circuit for said stick relay closed only when the vehicle is substantially at a stop, and trackway means at spaced points for momentarily energizing said main relay under unfavorable traffic conditions to reset said control device a predetermined amount whereby said manually operable means must be operated at said spaced points under unfavorable traffic conditions to prevent the de-energization of said stick relay and said brake applying device, and a consequent automatic brake application.
10. In an automatic train control system of the continuous inductive type, the combination with a relay energized under clear traffic conditions in response to current flowing in the track rails, of a distance device operable in accordance with the progress of the vehicle and controlled to be operated in accordance with such progress in one direc-
- tion when said relay is energized and in the other direction when said relay is de-energized, and brake control means governed by said distance device.
11. In an automatic train control system of the continuous inductive type, the combination with a relay energized under clear traffic conditions in response to current flowing in the track rails, of a distance device operable in accordance with the progress of the vehicle and controlled to be operated in accordance with such progress in one direction when said relay is energized and in the other direction when said relay is de-energized, the rates of such operation being different in the two directions, and brake control means governed by said distance device.
12. In an automatic train control system of the continuous inductive type, the combination with a relay energized under clear traffic conditions in response to current flowing in the track rails, of a distance device operable in accordance with the progress of the vehicle and controlled to be operated in accordance with such progress in one direction when said relay is energized and in the other direction when said relay is de-energized, the rate of operation in said one direction being greater than in said other direction and brake control means governed by said distance device.
13. In an automatic train control system of the continuous inductive type, the combination with a relay energized under clear traffic conditions in response to current flowing in the track rails, of a distance device operable in accordance with the progress of the vehicle and controlled to be operated in accordance with such progress in one direction when said relay is energized and in the other direction when said relay is de-energized, means for effecting an application of the brakes of the vehicle upon a predetermined extent of operation of said distance device, and manually operable means for preventing such application of the brakes.
14. Car-carried apparatus for automatic train control systems comprising, a distance device operated in accordance with the progress of the car, brake applying means controlled by the distance device, and means associated with the distance device for automatically preventing operation of the brake applying means until a predetermined distance of car travel after initiation of the distance device, means controlled by trackway conditions for driving the distance device in opposite directions at different speeds, the higher speed corresponding to energized trackway conditions and the lower to de-energized trackway conditions.
15. In a train control system, a car-carried relay energized under favorable traffic conditions ahead and de-energized under unfavorable traffic conditions ahead, a control

device arranged to be driven at a given rate in accordance with the progress of the car from an initial to a run down position when said relay is de-energized and be driven back to said initial position in accordance with the progress of the car if said relay be subsequently re-energized for a sufficient length of time, car speed restricting means initiated by said control device after a predetermined amount of movement toward run down position, brake setting means initiated after said control device has moved a predetermined amount toward run down position, acknowledging means for preventing initiation of said brake setting means if operated in time, and trackway means to only momentarily re-energize said relay under unfavorable traffic conditions to cause said control device to be driven but part way back to said initial position whereby to initiate said brake setting means at a point a given distance beyond said trackway means unless prevented from so doing by operation of said acknowledging means.

16. In a train control system, a car-carried relay energized under favorable traffic conditions ahead and de-energized under unfavorable traffic conditions ahead, a control de-

vice arranged to be driven at a given rate in accordance with the progress of the car from an initial to a run down position when said relay is de-energized and be driven back to said initial position at a faster rate than said given rate in accordance with the progress of the car if said relay be subsequently re-energized for a sufficient length of time, car speed restricting means initiated by said control device after a predetermined amount of movement toward run down position, brake setting means initiated after said control device has moved a predetermined amount toward run down position, acknowledging means for preventing initiation of said brake setting means, but not affecting said speed restricting means, if operated in time, and trackway means to only momentarily re-energize said relay under unfavorable traffic conditions to cause said control device to be driven but part way back to said initial position whereby to initiate said brake setting means at a point a given distance beyond said trackway means unless prevented from so doing by operation of said acknowledging means.

In testimony whereof I affix my signature.

WINTHROP K. HOWE.
